CLAIM

The ornamental design for a notebook computer with camera module, as shown and described.

DESCRIPTION

FIG. 1 is a perspective view of a notebook computer with camera module showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is a perspective view of the notebook computer with camera module in FIG. 1 in another position where the cylindrical portion of the camera module is rotated;

FIG. 10 is a perspective view of the notebook computer with camera module in FIG. 1 in another position where the cylindrical portion of the camera module is rotated; and,

FIG. 11 is a perspective view of the notebook computer with camera module in FIG. 1 in another position.

The dashed broken lines illustrate portions of the notebook computer with camera module and form no part of the claimed design.

1 Claim, 9 Drawing Sheets
